UNITED STATES PATENT OFFICE.

WILLIAM SCHACHT, OF BROOKLYN, NEW YORK.

IMPROVEMENT IN ROTARY STAMP-CANCELERS.

Specification forming part of Letters Patent No. 140,219, dated June 24, 1873; application filed
March 29, 1873.

To all whom it may concern:

Be it known that I, WILLIAM SCHACHT, of Brooklyn, in the county of Kings and State of New York, have invented a new and Improved Rotary Stamp-Canceler; and I do hereby declare that the following is a full, clear, and exact description of the same, reference being had to the accompanying drawing forming a part of this specification, in which—

Figure 1 represents a front view of my rotary stamp-canceler; Fig. 2, a vertical transverse section of the same on the line *c c*, Fig. 1; Fig. 3, a front view of the detached printing-roller open for the reception of the types; and Fig. 4, a vertical transverse section of the same, closed, on the line *x x*, Fig. 3.

The object of my invention is to furnish to brewers and others a convenient apparatus for canceling internal revenue and other stamps in a quick and expeditious manner, near the central part of the same. My invention consists in the mode of inserting and holding the type, as hereinafter described.

In the drawing, *A* represents the frame of my rotary stamp-canceler, to the upper part of which is secured an ink-receptacle, *B*, and below the same the inking-roller *C*. Directly above and parallel with the latter is printing-roller *D*. The ink-receptacle *B* is provided with a narrow outlet at its lower end, which outlet may be opened more or less by means of a sliding gate, *E*. An ink-distributer, *F*, of suitable material, is hung near to, and in

contact with, inking-roller *D*, as shown in Fig. 2. The spindle *a* of roller *D* moves in slots *b* and spiral springs *d*, for the purpose of inking evenly the type part of printing-roller *D*. The printing-roller *D* has side shoulders *e*, which, in connection with the pressure-roller *G*, hung in a suitable sliding frame below roller *D*, and acted upon by band or other spring *f*, carry the stamp-strips through, so that the stamps will successively be canceled by the rotation of roller *D*. The lid *H* is pivoted to the shoulders *e*, secured by pins *g* passing sidewise through them, and has the name of the firm upon it. It also has a recess, *O*, slightly conical, from the inside toward the outside, for the insertion and adjustment of the changeable types for dates, &c. Roller *D* has a slight recess, *O'*, which forms the base for the conical types, with their round faces and letters corresponding to those of the firm-name. Thus, no cutting of the paper of the stamps is produced.

Having thus described my invention, what I claim as new, and desire to secure by Letters Patent, is—

The printing-roller *D* having shoulders *e*, recess *O'*, and pivoted lid *H*, with conical recess *O* and pins *g*, for the purpose of inserting and holding the types, as described.

WILLIAM SCHACHT.
